UNITED STATES PATENT OFFICE.

JOSEPH A. RAMSEY, OF BEATRICE, NEBRASKA.

VEHICLE END-GATE.

1,135,844.

Specification of Letters Patent. Patented Apr. 13, 1915.

Application filed May 13, 1912. Serial No. 697,027.

To all whom it may concern:

Be it known that I, JOSEPH A. RAMSEY, a citizen of the United States, residing at Beatrice, in the county of Gage and State 5 of Nebraska, have invented a new and useful Vehicle End-Gate, of which the following is a specification.

The invention is embodied in the construction and combination of parts hereinafter 10 described.

The primary object of the present invention is the provision of an end gate of this character, in which a vertically swinging end gate is provided with oppositely extending 15 bails that limit the lateral extension of the two retaining wings or members, and permit of the folding of the members against the end gate when the end gate is closed.

In the accompanying drawing Figure 1 20 is a perspective view of the invention; Fig. 2 is a like view of the same in open or unloading-position; Fig. 3 is an end elevation thereof, the parts being in closed position; Fig. 4 is a sectional elevation of the device, 25 the parts being in open position.

In carrying out my invention, I provide the vehicle or wagon, the body-portion 1 of which is partially or fragmentarily shown, with a suitable end or tail gate or board 2 30 equipped at its top and bottom edges, upon the outside, with cleats or strips 3, said board or gate being suitably hinged at its bottom edge, as at 2^a, to the corresponding edge of the vehicle-body. Boards 4 are 35 secured vertically on the ends of the wagon-body sides, and to these are detachably hinged, by straps 5 and pintles 6, the triangular end sections or closures 8, which serve to hold the end-gate closed as in Figs. 1 and

3, or supported in open position, as in Figs. 40 2 and 4. Metal strips 8^a are secured to the edges of the triangular closures 8. Guards 12, consisting of metal strips forming elongated loops, are secured at their ends to the transverse cleats or bars 3 of the end-gate 45 and thus extend parallel to the side edges of the latter. When the end-gate 2 is closed, guards 12 prevent the sides of the wagon-body from spreading, and, when the end 50 and the triangular closures 8 are fastened in such position, they thus hold the end-gate closed, by means of the turn-button 19, which is attached to the end-gate and projects through slots in the closures. When the end-gate is open, as in Figs. 2 and 4, the 55 guards 12 serve as supports for the end-gate, since they then rest on the shoulders 8^b of the triangular closures 8, the latter being in such case swung out and projecting rearward of the wagon-body in parallel position. 60

What I claim is:—

The combination with a wagon body having side extensions, an end-gate, and triangular closures hinged to the side extensions of the wagon body—of U-shaped guards 65 secured to and projecting laterally from the side edges of the end-gate and adapted to embrace the side extensions of the wagon-body when the end-gate is closed, and to embrace and rest on the triangular closures 70 when the end-gate is opened.

In testimony that I claim the foregoing as my own, I have hereto affixed my signature in the presence of two witnesses.

JOSEPH A. RAMSEY.
